1 Claim

ABSTRACT OF THE DISCLOSURE

The invention relates to toys, and more particularly to toys of a circular design. The object resides in the provision of a toy made of two separate members attached to appear as two unattached members revolving in a substantially circular orbit in a vertical plane.

This invention relates to toys, and more particularly to a toy of circular design.

The primary object of this invention resides in the provision of a toy made of two separate members so constructed and attached as to appear as two unattached members when revolving in a substantially circular orbit in a vertical plane.

Another object of this invention resides in the provision of means to create the illusion that the substantially vertical orbit of one member induces a corresponding orbit of the other member.

Still further objects of the invention reside in the provision of a toy which is strong, durable, highly efficient in operation, simple in construction, and capable of being inexpensively produced.

For a complete understanding of the present invention, reference is made to the accompanying drawing of which:

FIG. 1 is a vertical front view of the toy.

With continuing reference to the accompanying drawing, the numeral 1 generally designates an outer rim of the toy made of a suitable plastic material, having a disc 2 attached to a portion of the inner surface of outer rim 1, an aperture 3 through the center of disc 2, and a string 4 whose ends are connected and received through aperture 3 in disc 2.

The toy is so constructed that the diameter of disc 2 is substantially equal to one half of the inside diameter of outer rim 1.

When string 4 is held in a substantially vertical position such that the greatest distance between disc 2 and the inner surface of outer rim 1 extends upwardly in relation to disc 2, and the outer rim is held against rotation, the toy is in a state of non-equilibrium.

When outer rim 1 is released, and string 4 is pulled upwards, the toy approaches a state of equilibrium such that the greatest distance between disc 2 and the inner surface of outer rim 1 rotates toward a downwardly extending position relative to disc 2.

If string 4 is lowered while disc 2 and outer rim 1 rotate, the toy approaches a state of non-equilibrium.

2

Continually raising and lowering string 4 at positions of non-equilibrium and equilibrium respectively, causes the toy to assume a continual substantially vertical orbit.

Since the attached portion of the toy is relatively small in relation to the unattached portion, continuous rotation creates the illusion that outer rim 1 and disc 2 are unattached.

Since the distance between disc 2 and outer rim 1 increases from zero to a distance substantially equal to one half of the inside diameter of outer rim 1, continuous rotation creates the illusion that the unattached portions of disc 2 and outer rim 1 continually touch at different points throughout rotation. Continuous rotation creates the illusion that the rotation of outer rim 1 is caused by the rotation of disc 2.

What is claimed as new is as follows:

1. A rim-disc toy comprising: a disc; an outer annular rim; a string means provided with connected ends; said disc provided with a central aperture; said string means received through said central aperture of said disc and extendable to a length greater than the maximal distance between said aperture and said outer rim; said disc being of a diameter substantially equal to one half of the inside diameter of said outer rim; said disc attached to inner surface of said outer rim; said attachment forming an eccentric embodiment; said eccentric embodiment rotably mounted on the horizontal portion of said string means received through said central aperture of said disc; said eccentric embodiment rotating in a vertical plane in response to up and down movements of said string means; said string means movements causing said disc to trace out a circular path of rotation about a horizontal axis through its center coexisting with the tracing out of an orbit about a horizontal axis through the center of said disc by said outer rim; said string means causing said horizontal axis of rotation of said disc to revolve about a point in space thereby causing said disc to trace out a circular orbit; said circular orbit of said disc and said eccentric orbit of said outer rim coexisting thereof producing the optical illusion that the circular orbit of said disc produces a force that causes said rim to assume an eccentric orbit about said disc causing said rim and said disc to appear as two separate and unattached members.
